US00D936504S

(12) **United States Design Patent** (10) **Patent No.:** **US D936,504 S**
(45) **Date of Patent:** **** Nov. 23, 2021**

(54) **TRACKING DEVICE**

(71) Applicants: **Wyatt Dick**, Fargo, ND (US); **Jeffrey L. Johnson**, West Fargo, ND (US)

(72) Inventors: **Wyatt Dick**, Fargo, ND (US); **Jeffrey L. Johnson**, West Fargo, ND (US)

(73) Assignee: **Appareo IoT, LLC**, Fargo, ND (US)

(**) Term: **15 Years**

(21) Appl. No.: **29/706,710**

(22) Filed: **Sep. 23, 2019**

(51) LOC (13) Cl. **10-04**

(52) U.S. Cl.

USPC **D10/70; D10/106.9**

(57) **CLAIM**

The ornamental design for a tracking device, as shown and described.

DESCRIPTION

FIG. 1 is a front perspective view of an embodiment of a tracking device showing the new design;

FIG. 2 is a rear perspective view of the embodiment of FIG. 1 showing the new design;

FIG. 3 is a rear view of the embodiment of FIG. 1;

FIG. 4 is a front view of the embodiment of FIG. 1;

FIG. 5 is a left side view of the embodiment of FIG. 1;

FIG. 6 is a right side view of the embodiment of FIG. 1;

FIG. 7 is a top view of the embodiment of FIG. 1; and,

FIG. 8 is a bottom view of the embodiment of FIG. 1.

The broken lines represent portions of the article that form no part of the claim.

1 Claim, 6 Drawing Sheets
